(57) **CLAIM**

The ornamental design for a luminaire with a holographic three-dimensional wave pattern, as shown and described.

DESCRIPTION

FIG. 1 is a bottom perspective view of an example embodiment of a luminaire with a holographic three-dimensional wave pattern, showing our new design; FIG. 2 is a top perspective view thereof; FIG. 3 is a front elevation view thereof; FIG. 4 is a partial cross-sectional view thereof; FIG. 5 is a left side elevation view thereof; FIG. 6 is a right side elevation view thereof; FIG. 7 is a top view thereof; and FIG. 8 is a bottom view thereof.

FIG. 9 is a bottom perspective view of another example embodiment of a luminaire with a holographic three-dimensional wave pattern, showing our new design; FIG. 10 is a top perspective view thereof;

FIG. 11 is a front elevation view thereof;

FIG. 12 is a partial cross-sectional view thereof;

FIG. 13 is a left side elevation view thereof;

FIG. 14 is a right side elevation view thereof;

FIG. 15 is a top view thereof; and,

FIG. 16 is a bottom view thereof.

The broken lines shown in the figures illustrate portions of the luminaire with a holographic three-dimensional wave pattern that form no part of the claimed design.

The space between the dash-dot-dash lines shown in the figures illustrate portions of the luminaire with a holographic three-dimensional wave pattern that form no part of the claimed design.

The dots shown on the surface of the lens in FIGS. 1, 4, and 8 indicate shading.

1 Claim, 14 Drawing Sheets
